UNITED STATES PATENT OFFICE

WASHINGTON A. KNOX, OF HEREFORD, TEXAS

RAIL COUPLING

Application filed October 13, 1930. Serial No. 488,431.

The object of this, my present invention, is the provision of a coupler for the meeting ends of railway rails which is of a construction and arrangement of parts to effectively hold the rails from tilting or from sinking and which will permit the rails moving toward or away from each other a distance only that required in the expansion and contraction of the rails.

10 A further object is the provision of a coupler for rails which will effectively join the rails and which will permit the rolling stock traveling thereover without jars or shocks, and in the same smooth manner as 15 the rolling stock travels over the heads at the body portions of the rails.

A further object is the provision of a coupler in the nature of a rail joint which can be readily applied to rails of the ordinary construction by slightly notching the heads of such rails at the confronting ends thereof.

To the attainment of the foregoing the invention consists in the improvement herein- 25 after described and definitely claimed.

In the drawings:

Figure 1 is a top plan view illustrating two rails coupled or joined in accordance with this invention.

30 Figure 2 is a side elevation looking toward the outer face of the coupler.

Figure 3 is a similar view looking toward the inner face of the coupler.

Figure 4 is a sectional view approximately 35 on the line 4-4 of Figure 1.

Figure 5 is a sectional view approximately on the line 5-5 of Figure 1.

Figure 6 is a detail perspective view of the sleeve member of the coupler.

40 Figure 7 is a perspective view looking toward the meeting ends of the rails.

Figure 8 is a perspective view of the filler plate for the inner sides of the rails.

Figure 9 is a similar view of the outer plate.

As disclosed by the drawings my improvement contemplates the employment of a sleeve member 1. The sleeve is in the nature of an ordinary rail chair, the same comprising a base 2 having its ends formed with up-

standing flanges that merge into inwardly directed angle flanges 3 and 4, respectively, and the space between the confronting faces of the flanges 3 and 4 and the base 2 is such as to snugly receive the base flanges 5 of the 55 confronting ends of the rails 6 therein. From their inner ends the flanges 3 and 4 are formed with upstanding plates 7 and 8, respectively. The plate 8 is extended from the flange 4 a greater distance than the plate 7 is extended from the flange 3 so that the inner face of the flange 8 will contact with the outer face of the heads of the rails. The space between the flanges 7 and 8 approximately equals that of the thickness of the 65 heads of the rails and, therefore, I arrange in the fishing spaces of the rails and in contact with the confronting faces of the flanges 7 and 8 filler plates 9 and 10, respectively. The inner faces of the rails have their heads 70 from points adjacent to their confronting ends notched or cut-away, as at 11, and the end walls provided by these notches are disposed at outward angles as indicated by the numeral 12. The outer filler plate 10 is centrally formed on its upper edge with an extension 13, and the end walls of the said extension are beveled inwardly, as at 14. The extension 13 of the plate 10 is designed to be received in the space provided by the 75 notches 11 so that the beveled end walls 14 of the said extension are disposed opposite but not in contact with the shoulders 12 provided at the ends of the notches 11. In a like manner the confronting ends of the rails are 80 slightly out of contact with each other.

There is passed through alining openings in the sides of the sleeve or chair, through the plates 9 and 10 and through the webs of the rails securing bolts 15 which are engaged by suitable nuts 16. Of course, the openings in the webs of the rails through which the bolts pass are elongated to permit of the necessary expansion and contraction of the rails without interfering with the joint or coupling therefor.

The sleeve or chair 1 is designed to rest upon one or more ties and to be spiked thereto, the heads of the spikes contacting with the top of the angle flanges 3 and 4, and the 100

shanks of the spikes may be received in grooves in the outer edges of the sleeve 1.

As disclosed by the dotted lines in Figure 4 of the drawings the flange 17 of a wheel of the railway stock is received between the inner faces of the heads of the rails and travels over but out of contact with the flange 7, while the tread 18 of the said rail will ride over the upper edge of the flange 8 of the sleeve. This, together with the broken joints provided by the shoulders 12 and the ends 14 of the extension 13 of the plate 10 insures a smooth riding of the wheels over the joint or coupler, and it will be noted that the elements comprising the joint or coupling are so connected together and so connected to the rails that the said rails cannot move longitudinally through the joint, while at the same time provision is made for the expansion and contraction of the rails. By properly spiking the sleeve member to the supporting ties for the sleeve it will be obvious that the joint will be held from sinking as well as from tilting or from lateral movement so that the joint not only insures easy traveling of the rolling stock but positively connects the rails and obviates the danger of the disconnection of rails at the confronting ends thereof.

It is believed the foregoing description when read in connection with the drawings will readily set forth the advantages of the construction to those skilled in the art to which the invention relates and while I have set forth a satisfactory embodiment of the improvement I desire to have it understood that I do not wish to be limited to the precise details herein set forth and, therefore, hold myself entitled to make such changes therefore as fairly fall within the scope of what I claim.

Having described the invention, I claim.

1. A coupling for the confronting ends of railway rails, comprising a sleeve including a base having inwardly directed flanges at the edges thereof which terminate in upstanding plates, the space between the flanges and the base of the sleeve being of a size to receive the base flanges of the confronting ends of rails therein, one of the upstanding flanges being of a greater height than the other and designed to contact with the outer faces of the heads of the rails and have its upper edge in a plane with that of the heads of the rails, filler plates filling the fishing spaces of the rails and contacting with the inner faces of the upstanding flanges and means comprising bolts and nuts for securing the rails to the upstanding flanges and filling plates.

2. A coupling for the confronting ends of railway rails, in which the heads of the said rails, from points adjacent to the end thereof have their inner faces cut-away in a line with their webs, comprising a sleeve to be spiked

on ties and which includes a flat base having its edges formed with inwardly directed flanges that merge into upstanding plates, one of said plates being of a greater height than the other and which last mentioned plate is designed to contact with the uninterrupted side of the heads of the rails when the rails are arranged in the sleeve and to have its upper edge flush with the tread surface of the rails, the cut-away heads of the rails being disposed over the shorter vertical flange, filler plates arranged in the fishing spaces of the rails and contacting with the inner faces of the upstanding flanges of the sleeve, the inner filler plate having an extension at the center thereof to be received in the cut-away portions of the heads of the rails, and means connecting the said flanges, the filler plates and the webs of the rails.

3. A coupling for the confronting ends of railway rails, in which the heads of the said rails, from points adjacent to the ends thereof have their inner faces cut-away in a line with the webs, the end walls of which being beveled outwardly, comprising a sleeve to be spiked on ties and which includes a flat base having its edges formed with inwardly directed flanges that merge into upstanding plates, one of said plates being of a greater height than the other and which last mentioned plate is designed to contact with the uninterrupted side of the heads of the rails when the rails are arranged in the sleeve and to have its upper edge flush with the tread surface of the rails, the cut-away heads of the rails being disposed over the shorter vertical flange, filler plates arranged in the fishing spaces of the rails and contacting with the inner faces of the upstanding flanges of the sleeve, the inner filler plate having an extension at the center thereof to be received in the cut-away portions of the heads of the rails, and means connecting the said flanges, the filler plates and the webs of the rails.

In testimony whereof I affix my signature.

WASHINGTON A. KNOX.
